UNITED STATES PATENT OFFICE.

ARTHUR B. CLUNIES, OF ROCHESTER, NEW YORK, ASSIGNOR TO THE SILL STOVE WORKS, OF SAME PLACE.

DESIGN FOR A WATER-FRONT.

SPECIFICATION forming part of Design No. 25,891, dated August 4, 1896.

Application filed June 18, 1896. Serial No. 596,082. Term of patent 14 years.

To all whom it may concern:

Be it known that I, ARTHUR B. CLUNIES, a citizen of the United States, residing at Rochester, in the county of Monroe and State of New York, have invented and produced a new and original Design for Water-Fronts for Stoves and Ranges, of which the following is a specification, reference being had to the accompanying drawings thereof.

10 Figure 1 is a perspective view of a water-front, showing my design; and Fig. 2, a plan view of the same.

The leading feature of my design consists of the shape and configuration of the ends of the water-front.

15 1 indicates the face of the water-front, curving slightly outward at one end, as at 2, to meet the surface 3, the outer portion of which is rounded slightly at 4 at the end. At the upper portion of the surface 3 is an angular

recess 5 and at the lower portion a projecting flange 6. One of the ends of the article is provided with the recess 7, the projecting lug 8, and the apertures 9.

The left end of the article, as shown in Fig. 25 1, has the slightly-curved face 19, curving outward at the bottom, as at 10, and the flange 11 beneath it, and is recessed at 12, and at the upper part is a recess 13, as shown more clearly in Fig. 2. The flange extension 14 on 30 the end is cut away at 15.

What I claim is—

The design for water-fronts for stoves and ranges, substantially as herein shown and described.

ARTHUR B. CLUNIES.
